(57) **CLAIM**

The ornamental design for a display screen with icon, as shown and described.

DESCRIPTION

FIG. 1 is a front view of a display screen with icon showing our new design;

FIG. 2 is a front view of the display screen with icon showing an alternative embodiment of our new design; and,

FIG. 3 is a front view of the display screen with icon of FIG. 1 shown on a device.

The broken line showing of the remainder of the user interface and the remainder of the display screen is for environmental purposes only and forms no part of the claimed design.
